DESIGN FOR A CASE FOR AN OPHTHALMIC MOUNTING

Edward M. Splaine, Southbridge, Mass., assignor to American Optical Company, Southbridge, Mass., a voluntary association of Massachusetts

Application November 6, 1933, Serial No. 49,656

Term of patent 14 years

To all whom it may concern:

Be it known that I, EDWARD M. SPLAINE, a citizen of the United States of America, residing at Southbridge, in the county of Worcester and State of Massachusetts, have invented a new, original, and ornamental Design for Case for an Ophthalmic Mounting, of which the following is a specification, reference being made to the accompanying drawing, forming a part thereof.

Fig. 2 is a perspective view of the case shown in Fig. 1.

I claim:

The ornamental design for a case for an ophthalmic mounting substantially as shown.

EDWARD M. SPLAINE.
